UNITED STATES PATENT OFFICE.

HENRY G. SAAL, OF CHICAGO, ILLINOIS.

EXPLOSIVE MISSILE.

1,320,991.

Specification of Letters Patent.

Patented Nov. 4, 1919.

Application filed July 30, 1918. Serial No. 247,357.

To all whom it may concern:

Be it known that I, HENRY G. SAAL, citizen of the United States, residing at Chicago, in the county of Cook and State of Illinois, 5 have invented a certain new and useful Improvement in Explosive Missiles, of which the following is a full, clear, concise, and exact description.

My invention relates to explosive missiles 10 and is of particular service when used in connection with shrapnel shells, though the invention is not to be limited to any particular character of missile and employs motors for effecting explosion. In the embodiment of the invention herein disclosed a 15 spring motor mechanically releases a firing hammer which in turn operates upon a firing cap, though I do not wish to limit my invention to a mechanical control of the explosion.

In carrying out my invention I employ a shell containing an explosive, a motor cage at the trailing end of the shell; means for firing the explosive in the shell, a pin in 20 controlling relation to said firing means whose shank projects away from the shell through the trailing end of the motor cage and whose inner end is adjacent to and in actuating relation with said firing means, a 25 motor, preferably a spring motor, within said motor cage in driving connection with the pin and operating therein in a direction to force the travel of the pin toward the firing means to fire said explosive, and a detent carried by 30 and engageable with the pin. When the invention is embodied in a missile whose explosion is mechanically effected the aforesaid pin is in the nature of a tripping pin and operates to release the firing hammer 35 that is within striking range of a detonating cap which is carried by a partition that separates the explosive containing shell from the motor cage. The detent is provided with a releasing lever adapted in one position to 40 permit the detent to hold the tripping pin against its operation by the spring motor and in another position to release such detent to permit the spring motor to move the tripping pin to hammer releasing position. 45 A delivery guide or tube is provided through 50 which the missile is discharged which guide has a formation to engage said lever to withdraw said detent to permit the spring motor to move the tripping pin to firing position.

as the missile is in travel. The extent of 55 travel of the pin while the missile is in transit is regulated by suitably withdrawing the pin away from the trailing end of the shell, the pin being held in its adjusted position by the detent and being allowed to move 60 when the detent is released on the passage of the missile through the delivery tube or guide. A missile equipped in accordance with my invention may be readily timed to explode while in transit and is also adapted 65 to be exploded by concussion upon striking the earth or the object toward which it is directed if the explosion does not occur beforehand.

The device of my invention is primarily 70 designed for use in aerial warfare but the invention is not to be restricted to this particular use. The missile may be dropped from an aeroplane toward another aeroplane and, by being timed to explode in 75 transit within fifteen feet above the second aeroplane its shrapnel or other parts will be effective in wrecking or effectively injuring the same. The missile, if exploding within suitable distance below the aeroplane will 80 operate to create an air pocket to disturb its equilibrium usually sufficiently to upset this aeroplane or at least to place its pilot at a tactical disadvantage. If the missile has not been properly timed to explode it will 85 continue its descent and strike the earth to be exploded by concussion. If a missile of this type is employed in aerial bombardment it should be timed to explode about fifteen feet above the ground or object, particularly if it 90 is a shrapnel shell structure as the shrapnel is most effectively scattered at this height above the object but if it should, before exploding, encounter mud or soft soil which is not itself capable of firing the missile the 95 mud will be penetrated until the harder earth below the mud is encountered to explode the missile by concussion.

I will explain my invention more fully by reference to the accompanying drawings 100 showing the preferred embodiment thereof and in which Figure 1 is a view in elevation of a missile of my invention shown within a delivery tube or guide that is illustrated in section; Fig. 2 is a view in sectional elevation of the upper portion of the missile illustrated in Fig. 1; Fig. 3 illustrates a modification of the structure appearing in Fig. 2;

Fig. 4 is a sectional view on line 4—4 of Fig. 2; Fig. 5 is a sectional view on line 5—5 of Fig. 2; Fig. 6 is a sectional view on line 6—6 of Fig. 2; and Fig. 7 is a sectional view on line 7—7 of Fig. 2.

Like parts are indicated by similar characters of reference throughout the different figures.

The shell 1, as shown, is a shrapnel shell containing bullets 2 of any suitable shape which surround the bursting charge 3 contained within the central tube 4. The motor cage 5 is at the upper or trailing end of the shell 1, these two elements being coupled by a joint ring 6 which is threaded upon its interior to have threaded engagement with the threaded exterior of the shell 1 and which ring is threaded upon its exterior to have threaded engagement with the threaded interior of the cage 5. The trailing end of the shell 1 carries a partition 7 which in turn carries two detonating caps 8 in the structure of Fig. 2 and one detonating cap in the structure of Fig. 3. In this second structure the shell 1 is smaller and has an external filling ring 1¹ for coupling the shell with the joint ring. In the structure of Fig. 2 the partition 7 is threaded into place whereas in the structure of Fig. 3 it is an integral part of the shell 1 and is shouldered to be clamped between the ring 1¹ and the plate 9 which, in both structures, is integrally formed with the ring 6, this plate having an opening 10 into which the striking end or ends of the cap or caps 8 project. The plate 9 constitutes a support for the mountings 11, 12 for the firing hammers 13 which are pivoted on said mountings at 14. Each firing hammer has a catch formation 15 engaged by a trigger catch 16 to hold the firing hammer in withdrawn or cocked position. Each firing hammer also has a cam formation 17 engaged by a leaf spring 18 for turning the firing hammer when the trigger catch 16 is released. In the structure of Fig. 2 each firing hammer is individual to one of the caps 8 and is not in striking relation to the other. Where only one cap is employed it is centrally disposed as illustrated in Fig. 3 on which account one of the firing hammers has its striking part 18¹ adjustably rotatable upon the balance of such hammer so as to bring the contact end thereof at the axis of the shell to strike the single cap of Fig. 3 or away from the axis of the shell to strike one of the two caps to which it is individual in construction of Fig. 2. By this arrangement a given motor cage with its equipment is adaptable to a shell having one pin or one having two pins. A binding screw 13² serves to secure the adjustment of the hammer part 18¹.

The trigger catches 16 are carried upon
65 triggers 19 in the form of jaws which are

normally held in engagement with each other by a retractile coiled spring 20, this spring serving to hold the trigger catches 16 in engagement with the firing hammers individual thereto. When the trigger jaws 19 are spread apart the trigger catches 16 are rotated toward each other to uncocking positions to permit the springs 18 to operate upon the cams 17, the springs then effecting the forceful movement of the firing hammers toward the detonating caps. Each hammer has a thumb piece 21 by which it may be engaged to be rotated into position to be held or cocked by the corresponding trigger catch 16. The upper ends of the jaws 19 are preferably so formed as to produce a conical pocket tapering toward the shell 1. The tripping pin has a conical head 22 and a shank 23, this head also tapering toward the shell 1. When the tripping pin is moved toward the shell 1 the head 22 finds its way between the trigger jaws and spreads them apart against the force of the spring 20 to release the trigger catches 16 thereby to permit the springs 18 to move the firing hammers individual thereto in their firing strokes. The shank 23 of the tripping pin projects away from the shell through the trailing end of the motor cage 5. This shank is formed with rack teeth engaged by a gear wheel or pinion 24 of a gear train which is driven by the spring motor 25. This gear wheel is driven in a direction to force the travel of the tripping pin toward the triggers to engage the inner end of the pin with the triggers to release the hammers. A plunger detent 26, carried by and projecting transversely of the motor cage, is engageable with the toothed shank of the tripping pin to hold this pin from movement by the spring motor toward the triggers. A detent withdrawing lever 27 is pivoted upon the exterior of the motor cage, this lever being connected with the detent and adjustable to extend either longitudinally or transversely of the detent and constructed, when longitudinal of the detent, to permit the spring 28 to force the detent 26 into holding engagement with the teeth upon the pin shank 23. When this trip lever is disposed transversely of the detent it operates to withdraw the detent from engagement with the shank of the tripping pin whereupon the spring motor is free to operate the train of gears and force the movement of the tripping pin into engagement with the triggers to release or uncock the firing hammers. The shank of the tripping pin also has a rack formation in driving connection with an index pinion 29 which has radial marks thereon indicating the distances through which the missile may be adapted to travel before exploding and, if desired, also the various lengths of time through which the missile may travel before 130

exploding. The index pinion 29 is desirably inclosed within a case 30 having a radial opening 31 therein in register with which the markings upon the index pinion 5 may be brought to determine the extent to which the pin projects through the trailing end of the motor cage and thereby the time required for such pin to travel before effecting explosion of the shell. The motor cage 10 is desirably provided with vanes 32 to aid in directing the missile in its travel. The missile is desirably passed through a delivery guide or tube 33 carrying a part in the path of the withdrawing lever 27 when such 15 lever is set to project longitudinally of the detent 26. As the missile passes through the delivery guide the lever 27 is turned to occupy a position transverse of the detent 26 as indicated by dotted lines in Fig. 2, 20 the lever in this position serving to withdraw the detent to permit the tripping pin to travel toward the triggers. The missile is automatically set to explode by being passed through the guide, the explosion 25 occurring at a measured interval, determined by the place where the detent engages the pin shank, after the missile passes through the delivery guide. The spring motor may be provided with a winding shaft 34 in alignment with a key hole 35 in the motor cage whereby the motor may be wound. The motor is desirably wound while the tripping pin is out of engagement with the gear wheel 24 at which time the head 22, 30 which has threaded connection with the shank of the pin, is removed. When the motor has been sufficiently wound the pin shank 23 is moved forwardly into mesh with the gear 24 whereafter the head 22 is 35 screwed into position. The abutment 36 upon the trailing end of the pin is engageable with the exterior of the motor cage to limit the extent to which the pin may be moved toward the shell. The finger ring 37 is swiveled to the abutment 36. By pulling upon this ring upwardly or rearwardly the tripping pin is withdrawn to the desired position indicated by the marking 40 upon the index pinion 29 that shows through the opening 31 in the casing for this pinion, the lever 27 at this time being transverse to the detent 26. When the pin has been withdrawn to the desired position said lever is brought into alignment with said detent to hold the pin against the action of the spring motor until the missile has been 45 dropped through the delivery guide 33.

The gear 24 should be driven at a uniform 50 rate of speed on which account I employ a speed governor which is preferably inclusive of a governor gear wheel 38 which is driven by but is preferably not included within the gear train. This wheel 38 is in 55 mesh with the worm 39 upon a governor

shaft 40. A collar 41 is fixed upon this shaft and a brake disk 42 is movable longitudinally of the shaft. Strip metal springs 43 couple the collar 41 with the hub of the disk 42. These springs carry weights 44 70 that respond centrifugally to the speed of the shaft 40. As the speed increases the disk 42 moves toward the collar 41 and toward the brake pad 45. When the disk encounters said pad the rotation of the shaft 75 40 is checked so that the gear train, and particularly the gear wheel 24, cannot move above the limiting speed which is determined by the position of said pad. This pad may be mounted upon a spring arm 46 in suitable connection with a rod 47 that is in threaded connection with a post 48 which is carried by and within the motor cage. A knurled knob 49 upon the exterior of the motor cage is in fixed connection with the 80 rod 47. This knob may be provided with an index or pointer 50 adapted to register with the speed indicating dial 51 to aid in the adjustment of the motor speed. 85

The entire structure may be provided with a guarding plate 52 normally covering the cap or caps 8 and intervening between them and the striking ends of the hammers so that if said hammers are accidentally dropped they cannot strike said pins. As the final step 90 in the preparation of the missile for its explosion, this plate is withdrawn to clear the path between the striking ends of the hammers and the caps. 95

To prevent the tripping lever from prematurely assuming a position transverse to the detent 26 I employ a square tube 53 which incloses the tripping lever and extends beyond its pivotal point whereby the tripping lever is preserved in alignment 100 with the detent. This square tube 53 slips over the inner end of the spring barrel 54 that incloses the spring 28 and serves to keep the lever 27 in alignment with such barrel and the detent 26 since such square tube surrounds not only the spring barrel but also surrounds said lever as indicated in Fig. 2. When it is desired to place the lever 27 at right angles to the detent the 105 square tube is slipped off the spring barrel sufficiently to permit said lever to turn. This lever is pivotally connected with the detent farther from either of the sides of the lever than the adjacent end of such lever so that when the lever is turned at right angles to the detent it will force a withdrawal of the detent against the force of the spring 28. 110

While I have herein shown and particularly described the preferred embodiment of my invention I do not wish to be limited to the precise details of construction shown as changes may readily be made without departing from the spirit of my invention, but 115 120 125 130

having thus described my invention I claim as new and desire to secure by Letters Patent the following:—

1. An explosive missile including a shell containing an explosive; a motor cage at the trailing end of the shell; a partition separating said shell and cage; a firing hammer; a trigger mounted in said motor cage for releasing said hammer; a detonating cap carried by said partition for firing the explosive in the shell and having its striking end accessible to said hammer; a tripping pin whose shank projects away from the shell through the trailing end of the motor cage and is formed with rack teeth and whose inner end is adjacent the trigger and is adapted to engage the same to release the hammer; a spring motor within said motor cage; a gear train driven by the motor and including a gear wheel meshing with rack teeth upon the shank of the tripping pin and turning in a direction to force the travel of the tripping pin toward the trigger to engage the inner end of the pin with the trigger to release the hammer; a plunger detent carried by and projecting transversely of the motor cage to be engageable with teeth upon the tripping pin; a pivoted detent withdrawing lever upon the exterior of the motor cage connected with the detent and adjustable to extend either longitudinally or transversely of the detent and constructed, when longitudinal of the detent, to permit of the engagement of the detent and pin and when transverse of the detent to withdraw it; and an index pinion mounted upon the exterior of the motor cage and operated by the shank of the pin, in combination with a delivery guide carrying a part to engage said lever to withdraw said detent.
2. An explosive missile including a shell containing an explosive; a motor cage at the trailing end of the shell; a partition separating said shell and cage; a firing hammer; a trigger mounted in said motor cage for releasing said hammer; a detonating cap carried by said partition for firing the explosive in the shell and having its striking end accessible to said hammer; a tripping pin whose shank projects away from the shell through the trailing end of the motor cage and whose inner end is adjacent the trigger and is adapted to engage the same to release the hammer; a spring motor within said motor cage in driving connection with the tripping pin and operating therein in a direction to force the travel of the pin toward the trigger to engage the inner end of the pin with the trigger to release the hammer; and a detent carried by and engageable with the tripping pin.
3. An explosive missile including a shell containing an explosive; a motor cage at the trailing end of the shell; a partition separating said shell and cage; a firing hammer; a trigger mounted in said motor cage for releasing said hammer; a detonating cap carried by said partition for firing the explosive in the shell and having its striking end accessible to said hammer; a tripping pin whose shank projects away from the shell through the trailing end of the motor cage and is formed with rack teeth and whose inner end is adjacent the trigger and is adapted to engage the same and release the hammer; a spring motor within said motor cage; a gear train driven by the motor and including a gear wheel meshing with rack teeth upon the shank of the tripping pin and turning in a direction to force the travel of the tripping pin toward the trigger to engage the inner end of the pin with the trigger to release the hammer; and a plunger detent carried by and projecting transversely of the motor cage to be engageable with teeth upon the tripping pin.
4. An explosive missile including a shell containing an explosive; a motor cage at the trailing end of the shell; a partition separating said shell and cage; a firing hammer; a trigger mounted in said motor cage for releasing said hammer; a tripping pin whose shank projects away from the shell through the trailing end of the motor cage and whose inner end is adjacent the trigger and is adapted to engage the same to release the hammer; a spring motor within said motor cage in driving connection with the tripping pin and operating therein in a direction to force the travel of the pin toward the trigger to engage the inner end of the pin with the trigger to release the hammer; and a detent carried by and engageable with the tripping pin.
5. An explosive missile including a shell containing an explosive; a motor cage at the trailing end of the shell; a partition separating said shell and cage; a firing hammer; a trigger mounted in said motor cage for releasing said hammer; a detonating cap carried by said partition for firing the explosive in the shell and having its striking end accessible to said hammer; a tripping pin whose shank projects away from the shell through the trailing end of the motor cage and is formed with rack teeth and whose inner end is adjacent the trigger and is adapted to engage the same and release the hammer; a spring motor within said motor cage; a gear train driven by the motor and including a gear wheel meshing with rack teeth upon the shank of the tripping pin and turning in a direction to force the travel of the tripping pin toward the trigger to engage the inner end of the pin with the trigger to release the hammer; and a plunger de-

tent carried by and projecting transversely of the motor cage to be engageable with teeth upon the tripping pin; and a detent withdrawing lever, in combination with a 5 delivery guide carrying a part to engage said lever to withdraw said detent.

6. An explosive missile including a shell containing an explosive; a motor cage at the trailing end of the shell; a partition separating said shell and cage; a firing hammer; a trigger mounted in said motor cage for releasing said hammer; a tripping pin whose shank projects away from the shell through the trailing end of the motor cage and whose 10 inner end is adjacent the trigger and is adapted to engage the same to release the hammer; a spring motor within said motor cage in driving connection with the tripping pin and operating therein in a direction to force the travel of the pin toward the trigger to engage the inner end of the pin with the trigger to release the hammer; a detent carried by and engageable with the tripping pin; and a detent withdrawing lever, in combination with a delivery guide carrying a part to engage said lever to withdraw said detent.

7. An explosive missile including a shell containing an explosive; a motor cage at the trailing end of the shell; means for firing the explosive in the shell; a pin in controlling relation to said firing means and whose shank projects away from the shell through the trailing end of the motor cage and is formed with rack teeth and whose inner end is adjacent to and in actuating relation with said firing means; a spring motor within said motor cage; a gear train driven by the motor and including a gear wheel meshing 20 with rack teeth upon the shank of the pin and turning in a direction to force the travel of the pin toward the firing means to fire said explosive; a plunger detent carried by and projecting transversely of the motor 25 cage to be engageable with teeth upon the pin; a pivoted detent withdrawing lever upon the exterior of the motor cage connected with the detent and adjustable to extend either longitudinally or transversely or 30 the detent and constructed, when longitudinal of the detent, to permit of the engagement of the detent and pin and when transverse of the detent to withdraw it; and an index pinion mounted upon the exterior of 35 the motor cage and operated by the shank of the pin, in combination with a delivery guide carrying a part to engage said lever to withdraw said detent.

8. An explosive missile including a shell 40 containing an explosive; a motor cage at the trailing end of the shell; means for firing the explosive in the shell; a pin in controlling relation to said firing means whose shank project away from the shell through 45 the trailing end of the motor cage and whose

inner end is adjacent to and in actuating relation with said firing means; a spring motor within said motor cage in driving connection with the pin and operating therein in a direction to force the travel of the pin 70 toward the firing means to fire said explosive; a detent carried by and engageable with the pin; and a detent withdrawing lever upon the exterior of the motor cage connected with the detent and adjustable to permit or prevent the engagement of the detent and pin.

9. An explosive missile including a shell containing an explosive; a motor cage at the trailing end of the shell; means for firing 80 the explosive in the shell; a pin in controlling relation to said firing means and whose shank projects away from the shell through the trailing end of the motor cage and is formed with rack teeth and whose inner end 85 is adjacent to and in actuating relation with said firing means; a spring motor within said motor cage; a gear train driven by the motor and including a gear wheel meshing with rack teeth upon the shank of the pin 90 and turning in a direction to force the travel of the pin toward the firing means to fire said explosive; and a plunger detent carried by and projecting transversely of the motor cage to be engageable with teeth upon the 95 pin.

10. An explosive missile including a shell containing an explosive; a motor cage at the trailing end of the shell; means for firing the explosive in the shell; a pin in controlling relation to said firing means whose shank projects away from the shell through the trailing end of the motor cage and whose inner end is adjacent to and in actuating relation with said firing means; a spring 100 motor within said motor cage in driving connection with the pin and operating therein in a direction to force the travel of the pin toward the firing means to fire said explosive; and a detent carried by and engageable with the pin.

11. An explosive missile including a shell containing an explosive; a motor cage at the trailing end of the shell; means for firing the explosive in the shell; a pin in controlling relation to said firing means and whose shank projects away from the shell through the trailing end of the motor cage and is formed with rack teeth and whose inner end is adjacent to and in actuating 115 relation with said firing means; a spring motor within said motor cage; a gear train driven by the motor and including a gear wheel meshing with rack teeth upon the shank of the pin and turning in a direction to force the travel of the pin toward the firing means to fire said explosive; a plunger detent carried by and projecting transversely of the motor cage to be engageable with teeth upon the pin; and a 120

125

130

- detent withdrawing lever, in combination with a delivery guide carrying a part to engage said lever to withdraw said detent.
12. An explosive missile including a shell containing an explosive; a motor cage at the trailing end of the shell; means for firing the explosive in the shell; a pin in controlling relation to said firing means whose shank projects away from the shell through the trailing end of the motor cage and whose inner end is adjacent to and in actuating relation with said firing means; a spring motor within said motor cage in driving connection with the pin and operating therein in a direction to force the travel of the pin toward the firing means to fire said explosive; a detent carried by and engageable with the pin; and a detent withdrawing lever, in combination with a delivery guide carrying a part to engage said lever to withdraw said detent.
13. An explosive missile including a shell containing an explosive; a motor cage at the trailing end of the shell; means for firing the explosive in the shell; a pin in controlling relation to said firing means and whose shank projects away from the shell through the trailing end of the motor cage and is formed with rack teeth and whose inner end is adjacent to and in actuating relation with said firing means; a motor within said motor cage; a gear train driven by the motor and including a gear wheel meshing with rack teeth upon the shank of the pin toward the firing means to fire said explosive; a plunger detent carried by and projecting transversely of the motor cage to be engageable with teeth upon the pin; a pivoted detent withdrawing lever upon the exterior of the motor cage connected with the detent and adjustable to extend either longitudinally or transversely of the detent and constructed, when longitudinal of the detent, to permit of the engagement of the detent and pin and when transverse of the detent to withdraw it; and an index pinion mounted upon the exterior of the motor cage and operated by the shank of the pin, in combination with a delivery guide carrying a part to engage said lever to withdraw said detent.
14. An explosive missile including a shell containing an explosive; a motor cage at the trailing end of the shell; means for firing the explosive in the shell; a pin in controlling relation to said firing means whose shank projects away from the shell through the trailing end of the motor cage and whose inner end is adjacent to and in actuating relation with said firing means; a motor within said motor cage in driving connection with the pin and operating therein in a direction to force the travel of the pin toward
- the firing means to fire said explosive; and a detent carried by and engagable with the pin, in combination with a delivery guide carrying a part to engage said lever to withdraw said detent.
15. A firing device including a striking hammer and a trigger for cocking the hammer, said hammer having a portion adjustable with respect to the balance thereof to determine the place where the hammer is to strike.
16. A firing device including a striking hammer and a trigger for cocking the hammer, the striking portion of the hammer being adjustable to determine where the hammer is to strike.
17. An explosive missile including a shell containing an explosive; a motor cage at the trailing end of the shell; means for firing the explosive in the shell; a pin in controlling relation to said firing means and whose shank projects away from the shell through the trailing end of the motor cage and is formed with rack teeth and whose inner end is adjacent to and in actuating relation with said firing means; a motor within said motor cage; a gear train driven by the motor and including a gear wheel meshing with rack teeth upon the shank of the pin and turning in a direction to force the travel of the pin toward the firing means to fire said explosive; and a plunger detent carried by and projecting transversely of the motor cage to be engagable with teeth upon the pin.
18. An explosive missile including a shell containing an explosive; a motor cage at the trailing end of the shell; means for firing the explosive in the shell; a pin in controlling relation to said firing means whose shank projects away from the shell through the trailing end of the motor cage and whose inner end is adjacent to and in actuating relation with said firing means; a motor within said motor cage in driving connection with the pin and operating thereon in a direction to force the travel of the pin toward the firing means to fire said explosive; and a detent carried by and engageable with the pin.
19. An explosive missile including a shell containing an explosive; means for firing the explosive in the shell; a motor; a pin in controlling relation to said firing means and operated by said motor; a detent for preventing the pin from being operated by the motor; a detent withdrawing lever; and means for normally preventing operation of said lever.

In witness whereof, I hereunto subscribe my name this 25th day of July A. D., 1918.

HENRY G. SAAL.
